JP 1611149 S 8/2018

Primary Examiner — Marie D. Fast Horse

(57) **CLAIM**

The ornamental design for a payment machine, as shown and described.

DESCRIPTION

FIG. 1 is a front view showing a payment machine showing our new design;

FIG. 2 is a rear view thereof;

FIG. 3 is a left-side view thereof;

FIG. 4 is a right-side view thereof;

FIG. 5 is a top view thereof;

FIG. 6 is a bottom view thereof;

FIG. 7 is a front-bottom perspective view thereof; and,

FIG. 8 is a rear-top perspective view thereof.

The broken lines depict portions of the payment machine that form no part of the claimed design.

1 Claim, 4 Drawing Sheets(56)
